[57] CLAIM

The ornamental design for a baton carrier for use with belt, substantially as shown and described.

DESCRIPTION

FIG. 1 is a left side elevation view of a baton carrier showing my new design; the right side elevation view being a mirror image thereof;

FIG. 2 is a front elevation view thereof;

FIG. 3 is a bottom plan view thereof;

FIG. 4 is a front elevation view thereof, shown at a reduced scale, with the belt and baton shown in broken lines for illustrative purposes only;

FIG. 5 is a top plan view thereof; and

FIG. 6 is a rear elevation view thereof.
